UNITED STATES PATENT OFFICE.

FORD W. HARRIS, OF LOS ANGELES, CALIFORNIA, ASSIGNOR TO PETROLEUM RECTIFYING COMPANY OF CALIFORNIA, OF SAN FRANCISCO, CALIFORNIA, A CORPORATION OF CALIFORNIA.

DEHYDRATOR.

Application filed September 7, 1920. Serial No. 408,694.

To all whom it may concern:

Be it known that I, FORD W. HARRIS, a citizen of the United States, residing at Los Angeles, county of Los Angeles, and 5 State of California, have invented a new and useful Dehydrator, of which the following is a specification.

My invention relates to dehydrators, and the principal object of the invention is to 10 provide a device of this character by which liquids of different electrical conductivity and specific gravity may be readily separated.

A further object of the invention is to 15 provide a dehydrator which is especially adapted to separate water and oil, and which finds a special utility in the dehydration of petroleum emulsions. Petroleum emulsions as produced in the production 20 and transportation of oil consist of masses of oil in which globules of water are present. Where these globules are of such size as to be visible to naked eye, it is comparatively easy to separate the water and oil 25 by allowing the emulsion to stand, the oil being lighter than the water which settles readily in the bottom of the container. There are, however, emulsions in which the drops are so small that they are not visible 30 to the naked eye and in which are also drops which are probably too small to be seen with even the most powerful microscope. These very small drops of water will not settle out even if the emulsion is 35 allowed to stand for a long period, and it is a particular object of my invention to provide a dehydrator by which these very tight emulsions may be separated.

It is a well known fact that when an 40 emulsion is placed between electrodes, having an electrical potential impressed therebetween, that the water particles tend to coalesce and tend to form larger drops, this action continuing until the drops continue to be of sufficient size to readily settle 45 by gravity. It has been found, however, that unless the electrical potential between these charged electrodes is kept above a certain minimum which depends upon the 50 character of the oil, that the coalescing drops form numerous chains which in the aggregate short circuit the electrodes. The

minimum potential necessary depends upon the average size of the water particles, the finer the particles, the higher the necessary 55 potential. Where light oils of low specific gravity are involved, the size of the drop is always very small as the larger particles readily settle out, and the voltage must be excessive to prevent short circuiting. 60

I have found also where oil is subjected to a preliminary gravitational separation so that only very fine drops remain, that the voltage must be excessive. For example, on California emulsion as produced at the well, a potential of 11,000 volts is ordinarily sufficient to produce perfect dehydration action, but if these oils are allowed to stand in receivers for long times, 65 I have found that even 50,000 volts is not sufficient to prevent the formation of short circuiting chains. 70

I have further found that in the case of very light oils, the necessary voltage which prevents short circuiting may be in excess of 200,000 volts. It is extremely difficult to build apparatus on which these excessive voltages may be carried, and it is a further object of my invention to provide a dehydrator which will treat very tight and stubborn emulsions with a voltage very much lower than that which would be otherwise necessary. This I accomplish by 75 agitating the emulsion in the electric field. I am aware that previous inventors have proposed to use agitation for this purpose, but so far as I am aware, all previous types of apparatus designed for this purpose have been open to objection in that they were 80 subject to a very considerable fire risk. This has been due to the fact that previous inventors have found it necessary, due to the peculiar construction of their apparatus, to dehydrate in tanks which were open to 85 the atmosphere. 90

It is a further object of my invention to provide a dehydrator in which charged electrodes are placed and in which the emulsion is agitated in the electric field. This, 100 I accomplish by rotating one of the electrodes. I am aware that previous inventors have provided a rotating electrode for this purpose, but they have considered it

necessary to insulate this rotating electrode from the tank structure, and they have met with many difficulties in providing an electrode which could be rotated and at the same time insulated against the potentials of 10,000 volts or more which it is necessary to employ. This I obviate by providing a stationary inner electrode which is insulated from the tank surrounding this electrode with a rotating outer electrode which is grounded to the tank proper. By providing a structure of this character, I am thereby able to provide a closed tank thus shutting off the oil from all contact with the air and preventing explosions and fires.

In previous types of hydrator, using rotating electrodes, it has been thought necessary to provide an auxiliary settling tank and to pass the emulsion downwardly through the treater. I have found that it is entirely possible to treat many kinds of oil and settle out the water in the same apparatus.

It has been found that in all types of electric dehydrators, that there is a tendency for short circuiting chain to form when the dehydrator is first filled with very wet oil, but if the circuit is momentarily interrupted, especially where the emulsion is in motion that these chains are broken up. I have further found that during the formation of these chains that the coalescence takes place and that after the short circuiting chains have formed within the dehydrator, it is completely short circuited and no further dehydrating action takes place.

It is a further object of my invention to provide means for interrupting the circuit to the dehydrator during predetermined intervals, in the event that the current flowing between the charged electrodes in the dehydrator exceeds a certain predetermined value.

A further object of my invention is to provide means for shutting off the flow of oil to the dehydrator whenever the current exceeds a certain value.

Further objects and advantages will be made evident hereinafter.

Referring to the drawings which are for illustrative purposes only,

Fig. 1 is a side elevation partly in section of a diagrammatic form of my invention.

Fig. 2 is a section on a plane represented by the line 2-2 of Fig. 1.

In the embodiment of my invention shown, 1 is a tight tank having an oil inlet pipe 2, a clean oil outlet pipe 3, and a water outlet pipe 4. Suspended on an insulator 5 from the top 6 of the tank by means of a rod 7, is an inner cylindrical stationary electrode

8, the space 9 between this electrode and the tank 1 being where the major portion of the dehydration takes place. Surrounding this electrode 8 is an outer rotating electrode 10 which is formed of angle irons 11 secured to a ring 12 at the top and to a spider 13 at the bottom, the spider 13 having arms 14 secured to a hub 15. The ring 12 bears against bearing plate 16 secured inside the tank 1 and the spider 13 is supported on a shaft 17 turning in a bearing 18, and having a bevel gear 19. The bevel gear 19 meshes with a bevel gear 20 carried on a shaft 21 which passes through a stuffing box 22 in the side of the tank 1 and which is driven by a pulley 23, the pulley 23 being driven by any convenient source of power, not shown. The shaft 21 is supported in bearing 24 carried on plate 25, on which the bearing 18 is also carried. The emulsion inlet pipe 2 communicates with a ring 26 having perforations 27 in the upper surface thereof through which the emulsion is distributed evenly around the outside of the tank 1. The water outlet pipe 4 communicates through a valve 28 with a vertical riser 29 which is vented at the top as shown at 30 and which communicates with a second riser 31 which communicates through a pipe 32 with a suitable drain, not shown. An electrical potential may be impressed between the stationary electrode 8 and the rotating electrode 10, by means of a transformer 33 having a primary 34, and a secondary 35. The secondary 35 is connected through a wire 36 with the rod 7, which passes through the insulator 5, the secondary 35 also being connected with the tank 1. The rotating electrode 10 is solidly grounded to the tank 1, the stationary inner electrode 8 being insulated by the insulator 5. The secondary 35, in practice, impresses from five to fifteen thousand volts between the electrodes 8 and 10, this potential depending somewhat on the character of the emulsion to be treated, there being an economical voltage for a certain production. The primary 34 may be supplied with alternating current at 110, 220, and 550, or at any commercial voltage. Connected in series with the primaries 34 is a coil 38 of an overload relay. Extending inside the coil 38 is a core 39 into which projects a stem 40 which carries moving contacts 41. The moving contacts 41 normally rests against and connects contacts 42 which are also in series with the coil 38 and the primary 34. The stem 40 is provided with a head 43 which extends into a recess 44 in the core 39 as shown in Fig. 1. On the lower portion of the stem 40 is a plunger 45 moving in a dash pot 46, having a check valve 47. Also connected in series with the coil 38, the primary 34 and the contacts 42 is a coil 48 of an electrically operated valve 49. The coil 48 acts upon a core

50 which tends to hold a valve member 51 in the position shown, thus opening a passage from an emulsion inlet pipe 52 into the emulsion inlet pipe 2. A reactance 53 is also 5 connected in series with the secondary 34.

The method of operation is as follows:

Pipe 52 is connected to the source of emulsion supply, emulsion being forced by a pump or by gravity through the pipe 52 10 and pipe 2 into the ring 26 and through the perforations 27 into the lower portion of the tank 1. Any air which may be in this tank is forced outwardly through the pipe 3 and which is at the extreme top of the 15 tank. Whenever the tank is filled, all air is excluded therefrom and there is no danger of explosion. Current being supplied to wires 54 and 55 at any convenient voltage and frequency, this current passes from 20 the wire 55 across the contacts 42 through the coil 48 through the coil 38 through the primary 34, the reactance 53 and back to the wire 54 to the source of supply. A certain potential is induced in the secondary 35 25 and an alternating electro-motive force is impressed between the stationary inner cylindrical electrode 8 and the rotating outer electrode 10. This outer electrode 10 is rotated at a slow rate of speed, say at fifty 30 revolutions per minute. The angle irons 11 are inclined as shown in Fig. 1. The entire body of emulsion, oil and water in the tank 1 is therefore set into slow rotation about the axis of the tank 1 due to the impelling action of the angle irons 11. Due 35 also to the inclination of these angle irons, the emulsion is forced downwardly in the space 9, the direction of rotation being in a counter clockwise direction as viewed in 40 Fig. 2. There are, therefore, two motions, first the rotation of the emulsion, and secondarily, a circulation of emulsion which flows downwardly between the electrode 8 and the tank 1, in the space 9, and upwardly 45 inside the electrode 8. During this very slow circulation, water tends to drop out of the oil falling in the bottom of the tank 1 and the clean oil tends to rise to the extreme top of the tank, being withdrawn 50 through the pipe 3. In the event chains start to form, short circuiting the electrodes, the current becomes excessive and the core 39 is pulled violently up in the coil 38. During the earlier portion of its movement, 55 the core 39 moves freely with relation to the stem 40 but as soon as the core strikes against the head 43, it pulls the stem 40 upwardly. The stem 40 and its attached parts are relatively light as compared to 60 the core 39 and the kinetic energy of the core 39 tends to pull these parts upwardly although the direct circuit to the coil 38 is interrupted as soon as the contacts 41 leave the contacts 42. This upward movement of the stem 40 is not retarded by the

dash pot 46 due to the fact that the check valve 47 opens and allows air to enter the interior of the dash pot freely. As soon, however, as the core 39 drops upon the stem 40, due to the interruption of the current 70 to the coil 38, and to the interruption of the magnetic force which had previously pulled the core 39 upwardly, the check valve 47 closes and the dash pot 46 prevents the rapid falling of the core 39 and the contacts 75 41. The dash pot is so set that it takes several seconds, possibly twenty seconds for the contacts 41 to re-establish the circuit. Under normal conditions, the valve 49 is open, the coil 48 being so constructed that 80 the core 50 is held in its upper position on a very small current, that is, on a current which is much less than that taken by the dehydrator under normal operating conditions. Whenever this current is interrupted 85 by opening of the contact 41, or by failure of voltage supply, the valve 49 closes and interrupts the flow of emulsion into the treater. By interrupting the circuit to the transformer 33 whenever short circuiting 90 chains form, and by simultaneously shutting off the flow of emulsion to the treater, I am able to break down the short circuiting chains and to give the water an opportunity to settle. When a very wet oil 95 is being supplied to the treater, the contacts 41 may open, almost instantly, after being closed, the circuit being open a very large proportion of the time. Under these conditions due to the electrically operated 100 valve 49, very little emulsion will be supplied to the treater and the capacity will be small. Whenever the treater has gotten into normal operating shape, however, the contacts 41 will remain closed practically all 105 of the time and the valve 49 will remain open practically all the time.

During the operation of the treater, there is a continuous settling of water inside the treater in the space inside the electrode 8 110 and in the space above the electrode 8. This water falls in the bottom of the treater and rises in the pipe 29. The height of this pipe is made sufficient to allow water to pass therethrough, providing the treater is 115 full. The point of junction between the pipes 29 and 31 is on the same level as the top of the treater. In practice the valve 28 may be regulated by hand or automatically to withdraw this water at a constant 120 rate so long as emulsion is supplied to the treater. Whenever the supply of emulsion ceases due either to the closing of the valve 39 or other causes, and the level of the oil in the treater tends to fall below the top 125 thereof, the flow of water is immediately shut off as there is not sufficient hydrostatic head to force it over the point of junction of the pipes 29 and 31.

I have found that by using an entirely 120

closed tank, I am able to prevent fires and explosions as the oil is not exposed to the air and the vapors produced from the oil are never mixed with oxygen inside the 5 treater or in the neighborhood of electrical discharges. By using a stationary inner electrode and a rotating outer electrode inside a stationary tank, I am able to greatly simplify the insulation problem, only one 10 insulator being necessary to support the inner electrode 8 and by reason of this greatly simplified insulation problem, I am able to make a tight tank and to eliminate the fire hazard, while at the same time preserving 15 the advantages to be gained from agitation. By providing means for automatically regulating the circuit externally and shutting off the flow of oil whenever conditions in the treater become unfavorable to dehydrat- 20 ion, I am able to automatically regulate the operation of the treater so that short circuiting does not become serious. I provide the reactance 53, however, in the circuit to the primary 34 for the purpose of control- 25 ling the maximum current which may occur during the momentary short circuiting period.

I claim as my invention:

1. In a dehydrator for petroleum emul- 30 sions, the combination of: a stationary tank; a stationary inner electrode in said tank, said inner electrode being insulated from said tank; an outer electrode, electrically connected to said tank and situated between 35 said tank and said stationary inner electrode; means for rotating said outer electrode; and means for impressing an electro-

motive force between said inner electrode and said outer electrode.

2. In a dehydrator for petroleum emul- 40 sions, the combination of: a stationary tank; an inner electrode in said tank; an outer electrode in said tank; means for rotating one of said electrodes; and means for impressing an electromotive force between 45 said electrodes.

3. In a dehydrator for petroleum emul- 50 sions, the combination of: an entirely en- closed stationary tank, an electrode in said tank; a shaft for rotating said electrode; a 55 fluid tight joint about said shaft where it passes through the walls of said tank; struc- ture forming a second electrode in said tank; and means for impressing an elec- tromotive force between said electrodes. 55

4. In a dehydrator for petroleum emul- 60 sions, the combination of: an entirely en- closed stationary tank; an electrode in said tank; a shaft for rotating said electrode; a fluid tight joint about said shaft where it 65 passes through the walls of said tank; struc- ture forming a second electrode in said tank; means for insulating said second elec- trode from said tank; and means for im- pressing an electromotive force between said 65 electrodes.

5. In a dehydrator the combination of: 70 an entirely enclosed stationary tank; an electrode in said tank; and means for ro- tating said electrode.

In testimony whereof, I have hereunto set my hand at Los Angeles, California, this 1st day of September, 1920.

FORD W. HARRIS.
